Primary Examiner — T Chase Nelson(74) *Attorney, Agent, or Firm* — Banner & Witcoff, Ltd.(57) **CLAIM**

The ornamental design for a shoe, as shown and described.

DESCRIPTION

FIG. 1 is a bottom front perspective view of a shoe showing my new design;

FIG. 2 is a bottom view thereof;

FIG. 3 is a bottom rear perspective view thereof;

FIG. 4 is an enlarged view of the design shown in FIG. 1 with environment removed for clarity;

FIG. 5 is an enlarged view of the design shown in FIG. 2 with environment removed for clarity;

FIG. 6 is an enlarged view of the design shown in FIG. 3 with environment removed for clarity;

FIG. 7 is a bottom front perspective view of the shoe of FIGS. 1-6 with shading removed;

FIG. 8 is a bottom view thereof; and,

FIG. 9 is a bottom rear perspective view thereof.

The broken lines within the shaded area represent grooves that form no part of the claimed design. The broken lines depicting the remainder of the shoe show features that form no part of the claimed design.
